(57) **CLAIM**

The ornamental design for a movable axle guard for a compactor wheel, as shown and described.

DESCRIPTION

FIG. 1 is a perspective view of a compactor wheel having a movable axle guard in accordance with an embodiment of the present invention.

FIG. 2 is a side elevational view of the compactor wheel of FIG. 1.

FIG. 3 is a top plan view of the compactor wheel of FIG. 1.

FIG. 4 is an end elevational view of the compactor wheel of FIG. 1.

FIG. 5 is a front elevational view of the compactor wheel of FIG. 1.

FIG. 6 is a cross-sectional side view of the compactor wheel taken along line 6—6 of FIG. 3; and,

FIG. 7 is an angled end elevational view of the compactor wheel of FIG. 1.

The broken lines shown in all figures are for illustrative purposes only and form no part of the claimed design.
